(57) **CLAIM**

The ornamental design for a vape battery with lid, as shown and described.

DESCRIPTION

FIG. 1 is a front perspective view of a vape battery with a lid in place;

FIG. 2 is a front perspective view of a vape battery with a lid removed;

FIG. 3 is a front perspective view thereof with environmental cartridge in place;

FIG. 4 is a left side view thereof with environmental cartridge in place;

FIG. 5 is a right side view thereof with environmental cartridge in place;

FIG. 6 is a front view thereof with environmental cartridge in place; and

FIG. 7 is a rear view thereof with environmental cartridge in place;

FIG. 8 is a top plan view thereof; and,

FIG. 9 is a bottom plan view thereof.

The broken lines in the drawings depict portions of the vape battery with lid that form no part of the claimed design.
